DESIGN FOR A CYCLE SADDLE

Benjamin N. Lobdell, Alma, Mich., assignor to
The Lobdell-Emery Manufacturing Company,
Alma, Mich., a corporation of Michigan

Application March 31, 1936, Serial No. 61,876

Term of patent 14 years

To all whom it may concern:

Be it known that I, Benjamin N. Lobdell, a citizen of the United States and resident of Alma, county of Gratiot, and State of Michigan, have invented a new, original, and ornamental Design for a Cycle Saddle, of which the following is a specification, reference being had to the accompanying drawing, forming a part thereof, and in which:

Figure 1 is a side elevation of the cycle saddle showing my new design;

Figure 2 is a rear elevation thereof; and

Figure 3 is a front elevation thereof.

I claim:

The ornamental design for a cycle saddle substantially as shown.

BENJAMIN N. LOBDELL.
